Patented Mar. 1, 1921.

Attorney

UNITED STATES PATENT OFFICE.

EDWARD BRUNHOFF, OF CINCINNATI, OHIO.

CHANGE-TRAY AND ADVERTISING DEVICE.

1,369,912.

Specification of Letters Patent.

Patented Mar. 1, 1921.

Application filed August 2, 1919. Serial No. 315,005.

To all whom it may concern:

Be it known that I, EDWARD BRUNHOFF, a citizen of the United States, residing at Cincinnati, in the county of Hamilton and 5 State of Ohio, have invented certain new and useful Improvements in Change-Trays and Advertising Devices, of which the following is a specification.

My invention relates to improvements in 10 change tray and advertising device. One of its objects is to provide an advertising device adapted to be placed in a variety of positions. Another object is to provide an improved combination of a glass, tile, or 15 similar advertising member and a detachable mounting or supporting member. Another object is to provide an advertising device substantially as above adapted to also be used as a change tray, and to facilitate 20 the removal of the change therefrom. My invention also comprises certain details of form, combination, and arrangement, all of which will be fully set forth in the description of the accompanying drawings, in 25 which:

Figure 1 is a perspective view of a change tray and advertising device embodying my improvements.

Fig. 2 is an end view of the same.

Fig. 3 is a sectional detail.

Fig. 4 is a diagram illustrating my device supported as an easel upon a table or similar support.

Fig. 5 is a diagram illustrating my device 35 supported in a hanging position against a wall.

The accompanying drawings illustrate the preferred embodiment of my invention, in 40 which 14 represents a member of plate-glass, tile, or similar material which carries an advertising design, ornamental design, portrait, or similar design or device. As illustrated for advertising purposes, and to also serve as a change tray when required, a 45 member 14 of plate-glass is employed, and the advertising matter in the form of a colored print is applied to and secured to the rear face so as to show through on the front, or upper face of member 14, and result in a particularly bright and pleasing 50 effect. The design may be however painted or enameled upon, or etched upon or otherwise developed upon the member 14. Notches 55 are preferably provided across the edges of opposite ends of member 14.

A mounting or supporting member 17 is formed preferably from sheet metal having sufficient resiliency so as to be sprung into and out of engagement with the member 14, and to normally grasp the member 14 at 60 opposite ends and to hold the member 14 firmly in position against accidental displacement. The middle portion of member 17 preferably constitutes an arch 18 at the rear of member 14 and between the feet 19 65 of the member 17, and at the same time provides a space into which the fingers of the left hand for instance may be introduced while the right hand of the customer is employed to sweep the change placed on member 14 by a dealer into the palm of the left hand. Opposite ends of member 17 form jaws 20 which yieldingly grasp or embrace the ends of the member 14 to hold it in place relative to member 17. The resiliency of the 70 metal through the arch 18 tends to draw the jaws 20 toward each other, and thus provides for yieldingly holding the member 14 in place, and also provides for the release 75 of the member, or its insertion by springing 80 said jaws apart a sufficient distance to enable the member 14 to be inserted or withdrawn. Each of the jaws 20 is provided with an inwardly directed projection 22 which enters one of the notches 15 as shown 85 in Fig. 3, and also in Fig. 2, thereby locking the member 14 against escaping edgewise at either end from the jaws 20. The arch portion of member 17 near one edge is perforated at 24, or if desired at 24', see Figs. 2 90 and 5, and has attached thereto by its opposite ends a loop of chain or cord 25, by means of which the advertising device may be hung upon the wall, substantially as indicated in Fig. 5.

The feet 19 have secured thereto sections 95 of textile material 26, which prevent noise, and also serve to prevent injury to a varnished or other surface 29 on which said feet may rest in the position Fig. 2. The 100 advertising device is also adapted to be positioned as an easel upon a table or other support 30 substantially as shown in Fig. 4, in which position the sections 26 serve to pad the sharp edge of the feet 19 of member 17, and thus prevent noise or injury to the surface on which the advertising device rests. The members 14 and 17 being separable, provide for interchangeably employing different members 14 with a single mem- 105 ber 17. The sections 26 are made of a flexible 110 material, such as cloth, which may be stretched over a frame, and may be attached to the feet 19 by any suitable means.

ber 17, or the reverse, which is of importance from a manufacturing view point. The devices are adapted to be shipped knock-down and assembled wherever required.

5. The device herein illustrated and described is capable of considerable modification without departing from the principle of my invention.

What I claim is.

10. 1. An advertising device comprising an advertising member having substantially parallel ends, and a supporting member extending beneath said advertising member having feet at opposite ends and jaws at 15 its opposite ends to resiliently and detachably engage opposite ends of said advertising member, said device being adapted to be supported in a variety of display positions.

2. An advertising device comprising an advertising member having substantially parallel ends, and a resilient sheet metal member to support said advertising member extending beneath said advertising member having jaws at its opposite ends to 25 resiliently and detachably engage opposite ends of said advertising member and feet

near opposite ends and intermediate of said jaws.

3. An advertising device comprising an advertising member, and a sheet metal supporting member of less width than said advertising member extending beneath said advertising member having jaws at its opposite ends to detachably engage opposite ends of said advertising member, feet near 30 opposite ends and intermediate of said jaws, and a resilient arch intermediate of said feet adapted to hold said jaws in yielding engagement with said advertising member.

4. An advertising device comprising an 40 advertising member having substantially parallel ends and cross-grooves therein, and a resilient sheet metal supporting member having feet near opposite ends and jaws at opposite ends to resiliently engage opposite 45 ends of said advertising member and the cross-grooves therein to lock said members together.

In testimony whereof I have affixed my signature.

EDWARD BRUNHOFF.
